CLAIM

The ornamental design for a pour over dripper as shown and described.

DESCRIPTION

FIG. 1 is a front and top perspective view of a pour over dripper, showing my new design.

FIG. 2 is a rear and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front and top perspective view of the pour over dripper in a usable state.

The dashed broken lines depict portions of the pour over dripper that form no part of the claimed design. The dashed broken lines in FIG. 9 show a spacer which is for the purposes of illustrating environment and forms no part of the claimed design.

1 Claim, 9 Drawing Sheets
